PRESTON M. HALL, OF WORCESTER, AND WOLCOTT REMINGTON, OF SWAMPSCOTT, MASSACHUSETTS, ASSIGNEES, BY MESNE ASSIGNMENTS, TO THOMSON-GIBB ELECTRIC WELDING COMPANY, A CORPORATION OF MASSACHUSETTS

NONSKID CHAIN

Application filed February 3, 1925. Serial No. 6,541.

Our invention relates to non-skid chains used upon vehicle wheels and more particularly to chains wherein provision is made for increasing the non-skid action by use of calks or pieces of metal attached to the links of the chain and affording wear or bite surfaces additional to those of the chain link itself or acting alone as the non-skid element engaging the road surface.

10 The object of the present invention is to provide a construction such that the calk and chain may be readily and cheaply manufactured by the employment of the electric resistance method of welding for firmly securing the calk to the chain link while at the same time avoiding the necessity of using special forms of calk or of bending the same to attach them. A further object is to provide a non-skid chain in which the calks shall 20 afford a maximum of wear surface thereby prolonging the life of the chain.

In the accompanying drawings:

Fig. 1 shows a cross member of a non-skid chain in plan of the general type to which 25 the invention is applied, some of the links being provided with calks applied according to our invention.

Fig. 2 is an edge view and partial section of Fig. 1.

30 Fig. 3 is a plan similar to Fig. 1 and shows the special form of bar forming the present invention.

Fig. 4 is an edge view and partial section of Fig. 3.

35 Referring to the accompanying drawings: The links of the cross members of the non-skid chains are indicated at 1. These cross members as usual in the art connect the side members extending circumferentially around 40 the tire or rim of the wheel and by engaging the road surface prevent skidding. Each link 1 of the cross member consists preferably as usual of a twisted link the corners of which in the ordinary way of the device bite into 45 the road surface. This enhances the efficiency of the chain in its non-skid action. It has been proposed to attach supplementary pieces of metal to each link, said supplementary pieces or calk co-acting with the corners of 50 the chain link in biting into the road surface

and in some cases being applied to the link with the purpose of strengthening the construction. In some instances said supplementary pieces have been attached by twisting their ends around the side members of 55 the link; in other cases the calks or pieces applied to the link have been blocks of metal inserted between the side members of the link and attached to the inner surface of said sides. In other instances the calks have consisted of a piece of metal welded to a side link and affording some increased biting surface but not acting to strengthen the link.

In our improved construction the difficulties and objections incident to such prior art 65 construction will be entirely avoided and the maximum of strength, ease of construction and long life of the chain are attained, together with increased ability to prevent side-wise skidding of the vehicle by affording 70 sharp edges or corners on the sides of the bar or rod forming the calk in contact with the roadway. This we accomplish by the aid of cross bars 2' of the form illustrated in Fig. 3 and acting as the calk and applied to the 75 outside of the chain link to bridge the cross members in a manner to permit them to be readily welded to the link by an electric resistance method wherein the parts are subjected to compression between welding elec- 80 trodes.

They may extend at right angles to axis of the chain link so as to engage the depressed portion of each twisted link or may be otherwise disposed as shown in Fig. (4). They 85 are of such length as to permit full contact with the outside surface of the chain link at which point the rounded surface of the link in conjunction with or independently of the round of the calk or bar affords the limited 90 initial contact desired for efficiency in welding. According to the present invention the cross bars or calks are rectangular in cross section as shown in Fig. (3). This form of calk in cross section affords a greater non-skid wear surface than the round section of calk and also will more readily bite into the surface of the roadway by its corners or longitudinally extending sharp edges which extend transversely of the cross member of the 100

non-skid chain and therefore resist any tendency of the wheel to which the chain is applied to move sidewise.

Furthermore it gives increased wear surface and increases the life of the chain and 5 additionally the corner which engages the link will assist in the welding operation since said corner causes the calk to engage the link by a very limited extent of contacting surface so that when the calk is applied by the electric resistance method the heating at the point of engagement or welding is greatly facilitated and the pressure applied will further cause the sinking of the bar or calk into the 10 surface of the link. The link of each calk 15 may be made so that it will extend up to or even beyond the side lines bounding the cross sides of the link and by so extending it, under some conditions, its biting or non-skidding effect will be enhanced. The cross bar or calk 20 may also be of such thickness that its wear surface will be above the corners of the chain link and will take the wear entirely or it may be substantially flush with said corners so as to coact with the chain link itself in the non-skid action. 25

The substantial advantage of our invention is that we avoid the necessity of bending the calk around the sides of the link and that it 30 is not necessary to insert it between the sides of the link as is required where the joints or welds between the calk and the sides of the link are made on the inside while at the same time additional advantages due to the 35 presence of the sharp corner extending along the edge of the angular bar parallel to the axis thereof and above referred to are secured. Furthermore by applying it and welding it to the outside, said calk is less liable to become detached than would be the case 40 if the joining were made, as proposed in some prior non-skid chains at a point between the sides where the impact on the calk would tend to force the calk through the link and there 45 is no sustaining effect of the link sides to prevent breakage of the joint. Also as may be seen the resistance method of welding may be much more readily conducted in our invention than in the case of a calk inserted in 50 the link since in the latter case it would be necessary to compress the link by a transverse pressure in order to effectively engage the calk and the link in the welding operation.

By making the cross bar of sufficient thickness to practically take the whole wear it is 55 obvious that the life of the chain may be greatly enhanced since the wear upon the corners of the link itself is avoided and weakening of the chain link itself will therefore 60 not take place until the thickness of the bar or calk has been greatly diminished by wear.

What we claim as our invention is:

A non-skid chain link formed as a metal 65 loop twisted to place the opposite sides at an angle to one another and having an attached

calk consisting of a bar of metal substantially rectangular in cross section and welded by its corners against the outer surface of the sides of the link transversely to the axis of the link, one such corner being welded to each side of the link, said bar having two of its edges exposed and directed away from said link to form non-skid edges effective to prevent skidding in either of two directions transversely to the length of said bar of metal. 75

Signed at Lynn, in the county of Essex and State of Massachusetts, this 26th day of January A. D. 1925.
